UNITED STATES PATENT OFFICE.

EMIL LAWRENZ, OF DETROIT, MICHIGAN.

CUTTER.

1,073,255.

Specification of Letters Patent. Patented Sept. 16, 1913.

Application filed July 5, 1912. Serial No. 707,684.

To all whom it may concern:

Be it known that I, EMIL LAWRENZ, a citizen of the United States, residing at Detroit, in the county of Wayne and State of Michigan, have invented certain new and useful Improvements in Cutters, of which the following is a specification.

This invention relates to cutters, and more especially to that class thereof which may 10 be utilized in connection with last-turning machines or the like, and it has for one of its objects the provision of a cutter-head comprising a series of cutters for acting upon the block to be turned after the rough 15 or superfluous material of the same has been removed, so that the present cutter-head has to produce only the finishing cut which leaves nothing but the sand-paper finish and polish to be applied to the work. 20 The invention has furthermore for its object the provision of what may be termed a secondary cutter-head in which a series of knives are positioned and held so as to successively operate upon the work and conform 25 in the size exactly to that of the model wheel of the machine.

A further object of the invention resides in the novel means for adjusting either one or all of said knives on the head in a "positive" manner so that they are held in fixed 30 positions without any danger of being displaced by centrifugal force.

Further objects of the invention will hereinafter appear and be particularly defined 35 in the claims.

The invention has been clearly illustrated in the drawings in which similar characters denote similar parts, and in which—

Figure 1 is a face view of a cutter-head 40 embodying my invention. Fig. 2 is a section on line 2—2 of Fig. 1. Fig. 3 is a face view of the head, *per se*, and Fig. 4 is a side view of one of the cutters.

In the present instance I have illustrated 45 a cutter-head 10 adapted to hold three knives 11^a, 11^b, 11^c, which are substantially similar in construction, and each of which comprises a cutting face the contour of which is round as shown at 12. The head 50 10 may be mounted upon a shaft 13 provided with a collar 14 against which the head rests, while a nut 15 in screwthreaded engagement with the outer end of the spindle may, in conjunction with a washer 16 55 serve to clamp the several cutters in place on the head, and the latter in its entirety in

contact with the collar 14. In the present instance I have illustrated two of the cutters 11^a and 11^b as being held in fixed positions on the head, as for instance dowel pins 17 which may be integral with and depend from the under-side of the cutters and fit snugly into apertures 18 provided in the disk for that purpose. One of the cutters (11^c), is mounted on the cutter-head 10 so 60 as to be adjustable thereon in an arcuate path to increase or decrease the distance between this cutting edge and the center of the spindle to a precisionized position, or in other words so that this particular cutter 65 will be adapted to be exactly of the same radius from the center of the spindle, as the radius of the model wheel from its axis. The other two cutters are intended more for the purpose of trimming the block into 70 shape so that only a very fine chip is required to produce a smooth or finished last. It is for the reasons just stated that this finishing cutter is in the present instance the only one which is adapted for fine adjust- 75 ment. 80

Owing to the great speed at which the cutters are revolved when operating, the means for holding the knives from being thrown outward by centrifugal force, must 85 be very substantial in construction, and furthermore great care must be exercised that the several knives will always be so positioned so as to retain the entire cutter-head in perfectly balanced condition. The particular manner in which the final finishing knife is held on the cutter-head is clearly 90 illustrated in Figs. 1 and 2 in which the dowel pins carried by the shank 12' are disposed within an arcuate slot 19 of the head, 95 this slot being curved eccentrically to the rotation axis of the head so that, when the knife is swung around the center of the spindle, the dowel pins will travel along in the slot 19, and a very fine adjustment of 100 the cutting edge 12' can therefore be obtained. The several knives being similar to each other, and the positions of the dowels being also the same in each case, it follows that the knives are interchangeable 105 and either knife may be placed over the slot 19 to produce the final cut and be brought into exact position by the slot construction above described. From a practical stand-point it is very undesirable that 110 all of the knives be made adjustable, on account of the extreme difficulty in setting

them at the same distance from the center. Furthermore these "adjustable" knives, while they do not do any actual finishing or sizing, will remove superfluous material 5 sidewise as the work is fed along and furthermore they serve to balance the cutter-head as a whole when the latter is rotated at a high speed.

Changes may be made in the general organization and particular construction of 10 the head or its component parts, especially in the shape of the cutters and the particular manner of positioning and holding them on the head, without departing from the 15 spirit of the invention.

I claim:—

1. The combination with a cutter-head having sets of apertures and an arcuate slot eccentrically disposed relatively to the rota-

tion axis of the head, of a knife having a 20 shank fitting against the head, dowel pins carried by the shank and fitted for movement in said slot and adapted to enter either set of apertures, and a single device for holding said shank against the head. 25

2. The combination with a head having sets of apertures and an oblique slot, of a series of knives each having a shank, dowel pins carried by each shank and adapted to enter either set of apertures or the slot, and 30 means for holding said knives in contact with the head.

In testimony whereof I affix my signature in presence of two witnesses.

EMIL LAWRENZ.
